ABSTRACT

A motor driven guillotine sharpener having a body in which at least a pair of grinding wheels are mounted for rotation about parallel shafts, the body being adapted to lie on the guillotine bed and means ensuring that the angle of the grinding wheels, when the device is on the bed, is the required bevel angle of the guillotine blade to be sharpened.

GUILLOTINE SHARPENER

BACKGROUND OF THE INVENTION

This invention relates to guillotine sharpeners and particularly for sharpeners for use with large industrial guillotines.

PRIOR TECHNIQUES

Industrial guillotines and particularly those used for cutting large stacks of paper or card stock need to be sharpened regularly and to the present time it has been usual to remove the blade from the guillotine for sharpening. This has been time consuming and in some operations it has meant that a guillotine has been non-operative for a period of each day. Where very regular sharpening is necessary, it would normally be essential to have at least two blades for a guillotine so that as soon as a blade is removed, it can be replaced with a sharpened blade and the removed blade later sharpened.

OBJECTS AND SUMMARY OF THE INVENTION

The object of the present invention is to provide an apparatus whereby a guillotine blade can be sharpened while still on the guillotine and which apparatus can be used by a relatively unskilled person to obtain consistent results and good sharpening.

The invention includes a guillotine sharpener having a body, a motor located within the body, at least two grinding wheels externally of the body, each grinding wheel being mounted for rotation about a shaft extending from the body, the axes of the shafts being parallel, a drive between the motor and the grinding wheels, the body having surfaces such that when on a bed of the guillotine, the grinding wheels are at an angle to the bed close to the required sharpening angle, and means on the body whereby the angle of the body relative to the bed, and hence the angle of the grinding wheels relative to the guillotine blade can be varied.

Preferably, the grinding wheels extend from one side of the body at an angle which may be of the order of 30° when the base of the body is resting on the bed and the adjustment means may comprise a vertical shaft passing through the body so as to partially rotate the body about a downwardly extending portion between the grinding wheels and the adjustment means and in one particular form, the length of this shaft may be such as to locate the grinding wheels at an angle of approximately 16° to the vertical and when fully extended.

An indicator means may be provided on the body whereby an indication of the pressure of contact of the wheels with the blade to be sharpened can be ascertained.

In order that the invention may be more readily understood and put into practice we shall describe one specific form of the device. This device will be described in relation to the accompanying drawings in which:

BRIEF DESCRIPTION OF THE DRAWINGS

FIG. 1 is a front view of the device;

FIG. 2 is a plan view;

FIG. 3 is a side elevation;

FIG. 4 shows an orientation of the device before the final adjustment for grinding occurs, and

FIG. 5 shows the device when grinding.

DETAILED DESCRIPTION OF THE INVENTION

Basically the device includes a body 1 which may be a hollow casting and mounted within the body is an electric motor 2, the shaft of which extends to front 3 of the device. The drive from the motor 2 is by means of a belt 4 which passes under a pair of idler pulleys 5 and around pulleys 6 which extend through the front face 3 onto the outer ends of which are attached grinding wheels 7. In the preferred form of the device, the grinding wheels may be approximately 3 inches in diameter and their axes may be spaced by approximately 9 inches. If preferred, the belt 4 may be ribbed and the shaft of the motor 2 and the pulleys 6 may be formed to engage with the ribs on the belt to thus give positive driving between the motor and the pulleys.

The lower cover of the body 1 carries a downward extension 9 which lies across a substantial portion of the width of the device.

- 20 Located in a tapped aperture in the rear of the body is a threaded shaft 10 having a finger grip portion 11 at its outer end, a lock nut 12 above the portion of the body through which it passes and a foot 13 beneath the body.
- 25 Mounted on top 14 of the body is a switch 15 and a load meter 16 which load meter gives an indication of the current drawn by the motor.

In operation, the guillotine clamp is held in its up position either by means of a control on the guillotine or 30 by placing a stack of paper under the clamp behind the blade and blade 17 is brought downwardly until it is located approximately 1½ to 2 inches from the guillotine bed. This will bring the blade into a position approximately centrally of the grinding wheels 7. It will be appreciated that guillotine blades normally lie at an angle to the bed but as they become close to the bed, this angle lessens and the angle when the blade is at approximately 1.5 to 2 inches from the bed has no effect on the operation of the sharpener except that the blade at 35 one end of movement of the sharpener will lie higher on the grinding wheels than at the other end.

The finger grip portion 11 of the shaft 10 is then adjusted until the grinding wheels are at the same angle as the bevel of the blade and this can be checked by 40 chalking the bevel and then moving the device across the blade to see whether chalk is removed. This position is as illustrated in FIG. 4 of the drawings. Once this location has been achieved, the angle of the grinding wheels to the vertical is increased by rotating the threaded shaft 10 by a predetermined number of times (say six) so that the grinding wheels are then located at 45 an angle to the body of the bevel and then contact only occurs adjacent the cutting edge of the blade. This position is as illustrated in FIG. 5 of the drawings. At the same time, the lock nut 12 is tightened and the tool is then set for use with the particular guillotine and, if it is to be used only with the particular guillotine, then the adjustment should not need re-setting.

The sharpener is then brought into light contact with the blade at one end, the motor is switched on and the sharpener running on the extension 9 and the foot 13 is moved across the blade. The pressure of contact is controlled by maintaining a constant reading on the load meter 16 and in one specific form of the invention, there is used a pressure such that the motor draws 0.5 AMPS above the non-load reading. When the sharpener reaches the other end of the blade, the motor is

shut-off. The blade can then be checked for sharpness and, if necessary, the contact and movement of the sharpener repeated, although there will be no need to adjust the device.

Some guillotine blades are formed with a microbevel at an angle to the main bevel of the blade and if this is the case, the grinding wheels 6 are located as accurately as possible against the microbevel rather than the bevel itself and a very slight increase in angle is obtained by rotating threaded shaft 10. The degree of increase may be approximately one-sixth the degree which is normally used any one time of the shaft 10.

If, after re-sharpening, the blade leaves uneven marks on the paper stack, these are caused by scoring on the back of the blade and have no relation to the sharpening. Often however, the scored metal can be removed by sharpening the blades slightly more.

If this scoring has occurred from the blade contacting the back of the clamp or from other external causes the scoring must be removed by honing or polishing the back of the blade either in or out of the machine.

It may be seen that the sharpening device of the present invention provides a rapid and accurate way of sharpening guillotine blades while still in position thus overcoming a large percentage of the normal expected downtime for such guillotines.

I claim:

1. A guillotine sharpener including a body, a motor located in the body, at least two grinding wheels exter-

nally of the body each grinding wheel being mounted for rotation about a shaft extending from the body, the axes of the shafts being parallel, a drive between the motor and the grinding wheels, the body having surfaces such that when on a bed of the guillotine, the grinding wheels are at an angle to the bed close to the required sharpening angle, and means on the body whereby the angle of the body relative to the bed, and hence the angle of the grinding wheels relative to the guillotine blade can be varied.

2. The guillotine sharpener as claimed in claim 1 wherein the grinding wheels extend from one side of the body and in which a threaded shaft extends through the body adjacent the other side, with the movement of the shaft altering the angle of the grinding wheels relative to the guillotine bed.

3. The guillotine sharpener as claimed in claim 2 wherein there is an extension on the underside of the body between the grinding wheels and the shaft, adjacent the grinding wheels, with the extension lying across a substantial part of the width of the base.

4. The guillotine sharpener as claimed in claim 1 wherein the are driven by means of a continuous belt.

5. The guillotine sharpener as claimed in claim 1 in which said motor is an electric motor and including means to measure the current drawn by the motor to control pressure of the grinding wheels.
